UNITED STATES PATENT OFFICE

158,109

HOMOGENIZING ATTACHMENT

Ira L. Lopata, Elizabeth, N. J.

Application September 4, 1946, Serial No. 133,047

Term of patent 3½ years

(Cl. D23—1)

To all whom it may concern:

Be it known that Ira L. Lopata, a citizen of the United States of America, and resident of the city of Elizabeth, county of Union, State of New Jersey, has invented a new, original, and ornamental Design for a Homogenizing Attachment, of which the following is a specification, reference being had to the accompanying drawing, forming part thereof.

Fig. 1 is a side elevational view of a homogenizing attachment embodying my new design;

Fig. 2 is a top plan view thereof;

Fig. 3 is a front elevational view thereof; and

Fig. 4 is a rear elevational view thereof.

I claim:

The ornamental design for a homogenizing attachment, substantially as shown.

IRAL. LOPATA.
